Primary Examiner—Sandra Snapp*Assistant Examiner*—Patricia Palasik(74) *Attorney, Agent, or Firm*—Drinker Biddle & Reath LLP(57) **CLAIM**

The ornamental design for a ceramic wear plate, as shown and described.

DESCRIPTION

FIG. 1 is a top view of an embodiment of a ceramic wear plate in accordance with my new design.

FIG. 2 is a front-side view of the embodiment of the ceramic wear plate shown in FIG. 1.

FIG. 3 is a back-side view of the embodiment of the ceramic wear plate shown in FIG. 1.

FIG. 4 is a right-side view of the embodiment of the ceramic wear plate shown in FIG. 1, the left-side view being a mirror image thereof.

FIG. 5 is a bottom view of the embodiment of the ceramic wear plate shown in FIG. 1.

FIG. 6 is a side perspective view as seen from the top of the embodiment of the ceramic wear plate shown in FIG. 1.

FIG. 7 is a side perspective view as seen from the bottom of the embodiment of the ceramic wear plate shown in FIG. 1; and,

FIG. 8 is a detailed partial view of the corner of the ceramic wear plate shown in circle 8 of FIG. 6.
